RECORDING OF ELECTRICAL IMPULSES

Glenn L. Dimmick, Haddonfield, N. J., assignor
to Radio Corporation of America, a corporation
of Delaware

Application June 25, 1938, Serial No. 215,910

10 Claims. (Cl. 179—100.3)

This invention relates to the recording of electrical impulses such as those of audio frequency, and has for its principal object the provision of an improved recording apparatus and method of operation whereby overshooting of adjacent records one onto the path of the other is avoided and the operation of such apparatus is simplified and improved. This application is in part a continuation of my application Serial No. 181,593, filed December 24, 1937.

The invention is more particularly adapted to the recording of plural track records such as those of the double-hump type, the push-pull type and the like. One of its distinguishing characteristics is the utilization of a pair of differently polarized light beams which are enlarged as the signal modulation increases. These beams are separated by an opaque area which is decreased in size as the signal modulation increases and which altogether disappears at extremely high signal modulation or overshooting. Although the use of polarized light is preferred, I may accomplish substantially the same result by using an appropriately complementary color screen.

In a preferred form of the invention, the differently polarized light beams are moved outwardly from the center of the record track in response to increase in the signal modulation and vice versa. Since the opaque area intermediate the adjacent records forms the inner edge of the adjacent record tracks and this opaque area is obliterated at overshooting or extremely high modulation, interference of one track with the other is altogether avoided.

In a somewhat different form of the invention, the differently polarized light beams may be utilized in conjunction with similarly differently polarized light slit areas, thus limiting the action of each beam to a separate area of the light slit and preventing interference of the adjacent record track areas.

The polarizing material utilized to produce these various effects may be of any suitable form such, for example, as the commercial product commonly known as "polaroid".

The invention will be better understood from the following description considered in connection with the accompanying drawings and its scope is indicated by the accompanying claims.

Referring to the drawings,

Figure 1 illustrates a system including a preferred form of the invention,

Figures 2, 3, 6 and 7 are fragmentary drawings illustrating the essential features of modified forms of the invention,

Figures 4 and 5 are explanatory diagrams relating to the distinction of the invention over somewhat similar prior art systems.

Figure 8 is a type of class A push-pull record produced by the arrangement of Figs. 6 and 7.

Figure 9 is a double hump record produced by a recording system of the type illustrated by Fig. 1, and

Figure 10 is a similar type of class A push-pull record produced by the arrangement of Fig. 3.

The recording system of Fig. 1 includes a pick-up device or microphone 13 from which the impulses to be recorded are supplied through amplifiers 11 and 12 to the operating coil 13 of a recording galvanometer 14. Light from a source 15 is projected through a lens 16, the triangularly shaped aperture of an aperture plate 17, a pair of differently polarized movable vanes 18 and 19 and lenses 20 and 21 to the mirror of the galvanometer 14.

The differently polarized vanes 18 and 19 are movable transversely of the aperture of the plate 17 and are illustrated as overlapping at their adjacent ends. The extent to which they overlap is determined by their control mechanism which is energized in accordance with the envelope current or volume of the recorded impulses. To this end, a component of the recorded impulses is supplied through a rectifier and filter network 22 to an operating coil 23 which acts through a lever 24 and a resilient member 25 to move the vane supporting arms 26 and 27 in response to change in the volume or amplitude of the recorded impulses. It will be observed that the lever 24 is pivoted at 26 and is biased by means of a spring 27 which opposes the pull of the coil 23 on the lever. Under these conditions the vanes 18 and 19 are moved transversely of the aperture of the plate 17 in accordance with the signal level. The light beams have their contour outlined by the non-overlapping areas 28 and 29, which vary in size in accordance with the signal level.

The differently polarized beams defined by the areas 28 and 29 are applied to the mirror of the galvanometer 14 and from this mirror are reflected to the recording surface 30 through the lens 21, the light slit of a plate 31 and lenses 32 and 33. The images of these differently polarized light beams are indicated at 34 and 35 on the light slit plate 31. Since the spacing between these images is determined by the overlapped or opaque area of the vanes 18 and 19, and this overlapped area is dependent on the level of the recorded impulses, it will be apparent that overshooting of the beams in a manner to cause in-

terference between the adjacent record tracks is avoided. The resulting type of record is shown in Fig. 9 wherein the two component records are indicated at 36 and 37 and the shading produced by the intermediate opaque area is indicated at 38. It will be observed that when the vanes 18 and 19 are moved outwardly to a point where they do not overlap, the intermediate opaque area 38 ceases to exist and the extension of one of the component records into the track normally occupied by an adjacent component record is prevented.

Fig. 2 illustrates a form of the invention in which a triangular-shaped light beam 39 is vibrated transversely of the light slit of the plate 31 in accordance with the impulses to be recorded, and a pair of polarized light beams 40 and 41 are overlapped at their adjacent ends and vibrated longitudinally of the light slit in accordance with the volume or envelope of the recorded impulses. With this arrangement, the overlapped central area of the light slit is opaque and the width of this area is increased and decreased longitudinally of the slit so as to variably shade the central part of the record in the manner previously explained in connection with Fig. 9.

Fig. 3 illustrates a similar modification of a recorder suitable for producing the class A push-pull record illustrated by Fig. 10. As in the modification of Fig. 2, the light beams 40 and 41 are overlapped at their adjacent ends and are vibrated longitudinally of the light slit in accordance with the volume of the signal to be recorded. The recording beam itself, however, is in the form of a trapezoid having its ends displaced with respect to one another. The operation of this modification of the invention will be apparent in view of the previous explanation. Thus, at relatively low modulation of the recorded impulses the differently polarized beams 40 and 41 are overlapped to a comparatively great extent and the central opaque portion 42 of the record is comparatively wide. At relatively high modulation of the impulses, however, this central opaque area 44 decreases in width and finally disappears at extremely high modulation which would otherwise produce interference between the adjacent record tracks 45 and 46.

Different prior art arrangements for recording a class A push-pull record are illustrated by Figs. 4 and 5. Thus, in Fig. 4, a light beam of the shape indicated at 47 is vibrated transversely of the light slit of the plate 31. It will be observed that the opposed ends of this beam are offset to prevent interference between the different record tracks. The type of record produced by this arrangement is indicated by the central area 48 of the record of Fig. 8. In the somewhat similar arrangement of Fig. 5, a pair of similarly shaped light beams 49 and 50 are vibrated transversely of the light slit of the plate 31. This arrangement, of course, results in a negative sound record which is the reverse of that produced by the arrangement of Fig. 4.

In the arrangement of Figs. 6 and 7, a pair of rectangular light beams 50 and 51 are vibrated longitudinally of the light slit of the plate 31 to produce a record such as that shown by Fig. 8. In this modification, the light slit has associated with its opposite halves differently polarized materials as indicated at 42 and 43 of Fig. 7, the light slit part 42, for example, being associated with the similarly polarized

beam 50 and the light slit part 43 being associated with the similarly polarized beam 51. At overshooting the polarized beams pass beyond the center of the slit and, of course, their light is excluded by the differently polarized light slit 5 section and interference of the records, one with the other, is thereby prevented as indicated in the record of Fig. 8.

In any of the above-described species of the invention, I may substitute a color filter for one of the polarizing screens and a complementary color filter for the other of said screens, the exact relation of the colors chosen depending upon the characteristics of the film which is to be used. For use with panchromatic film, I may use one filter of orange red and the other filter of greenish blue, while, for film sensitivity in the blue and near ultra violet regions only, I may use one filter which is transparent to the near ultra violet and not to the blue, and another filter which is transparent to the blue but opaque to the ultra violet and other combinations of filters that may be chosen according to the particular characteristics of the film. The filter, however, should preferably transmit light having approximately equal actinic effect upon the film so that the respective film areas will be exposed to the same degree. For instance, with an ortho type of film, if one filter has a high transmission in the blue, the band of transmission of this filter should be relatively narrow or its density should be relatively high, while the complementary filter should transmit as much of the spectrum as possible due to the lower sensitivity of the film to the other regions of the spectrum.

I claim as my invention:

1. An electrical impulse recorder including means for producing a plurality of light beams, means for differently polarizing said beams, means for modulating said beams in accordance with the impulses to be recorded, and means for varying the areas of said beams in accordance with the level of said impulses.

2. An electrical impulse recorder including means for producing a plurality of light beams, means including a pair of vanes movable in opposite directions for differently polarizing said beams, means for modulating said beams in accordance with the impulses to be recorded, and means for moving said vanes in accordance with the level of said impulses.

3. The combination of means for defining a light beam, means including a pair of partially overlapped vanes for converting said light beam to a pair of differently polarized light beams, means for modulating said pair of light beams in accordance with the impulses to be recorded, and means for varying the overlapping of said vanes in accordance with the level of said impulses.

4. An electrical impulse recorder including means for producing a plurality of differently polarized light beams, light slit means differently polarized as at its opposite ends, and means for vibrating said polarized beams transversely of said slit means in accordance with the impulses to be recorded.

5. The electrical impulse recording method which includes producing a plurality of differently polarized light beams, modulating said beams in accordance with the impulses to be recorded, and varying the size of said beams in accordance with said impulses.

6. An electrical impulse recorder including means for producing a plurality of light beams,

means including a pair of vanes movable in opposite directions each transparent to light of a characteristic to which the other is opaque, means for modulating said beams in accordance with the impulses to be recorded, and means for moving said vanes in accordance with the level of said impulses.

7. The combination of means for defining a light beam, means including a pair of partially overlapped vanes for converting said light beam to a pair of light beams having different characteristics, each vane being opaque to light having the characteristics transmitted by the other vane, means for modulating said pair of light beams in accordance with the impulses to be recorded, and means for varying the overlapping of said vanes in accordance with the level of said impulses.

8. An electrical impulse recorder including means for producing a plurality of light beams having different characteristics, light slit means having means at its opposite ends transparent to

light of one of said characteristics and opaque to light of the other of said characteristics, and means for vibrating said beams transversely of said slit means in accordance with the impulses to be recorded.

9. An electrical impulse recorder including means for producing a plurality of light beams, means including a pair of complementary color vanes movable in opposite directions for differently coloring said beams, means for modulating said beams in accordance with the impulses to be recorded, and means for moving said vanes in accordance with the level of said impulses.

10. The combination of means for defining a light beam, means including a pair of partially overlapped vanes for converting said light beam to a pair of differently colored light beams, means for modulating said pair of light beams in accordance with the impulses to be recorded, and means for varying the overlapping of said vanes in accordance with the level of said impulses.
